SOUND REPRODUCING SYSTEM

Sterling G. Sears, Garden City, N. Y., assignor to
 Dictograph Products Company, Inc., New York,
 N. Y., a corporation of Delaware

Application November 10, 1936, Serial No. 110,061

5 Claims. (Cl. 179—1)

This invention relates to sound reproducing systems, and more particularly to systems designed for the reproduction of sounds with a volume and quality adapted for perception by persons listening to the same through a damping transmitting medium.

More particularly, the invention relates to devices for reproducing sound that are adapted to be used in conjunction with ordinary sound reproducing systems, such as phonographs, radio receivers, and the like, whereby they meet the requirements of an individual listener hearing through selectively absorbent sound transmitting media.

15 The invention has for its object generally the provision of a system of the character indicated which is economical and efficient, is used in place of ordinary loudspeakers when one is listening through a damping transmitting medium and is adapted for reproducing sound so as to be perceived with natural tone quality.

20 A specific object of the invention is to provide a system of sound reproduction for use in conjunction with radio receivers, and the like, whereby each listener of a group may use a common source of electric energy and listen to a program of his or her selection to the exclusion of the other listeners.

Another object is to provide a device, preferably in the form of an attachment for use in conjunction with sound reproducing systems that is strong and durable and is adapted for producing sound with a desired propagation characteristic in a sound absorbent transmitting medium.

25 Still another object is to provide a system for reproducing sound in which the distortion that results from transmission through an intervening medium, such as air loaded with damping agents, is compensated so that the sound perceived has normal qualities.

Other objects of the invention will in part be obvious and will in part appear hereinafter.

The invention accordingly comprises the features of construction, combination of elements, and arrangement of parts, which will be exemplified in the construction hereinafter set forth and the scope of the invention will be indicated in the claims.

30 For a fuller understanding of the nature and objects of the invention reference should be had to the following detailed description taken in connection with the accompanying drawings, in which:

Fig. 1 is a view showing mainly diagrammatically a system of sound reproduction adapted for

the use of a plurality of individual listeners in accordance with the invention;

Fig. 2 is an enlarged sectional view showing the construction of the sound reproducing or speaking devices employed in Fig. 1;

Fig. 3 is a diagrammatic view showing volume-frequency characteristics of a speaking device that is constructed in accordance with the invention; and

Fig. 4 is a view, similar to Fig. 1, illustrating a modified form of the invention.

It is often desirable to provide facilities whereby individual listeners to radio programs, and the like, in a group in a room may listen to the program of his or her own selection to the exclusion of the others. To provide each listener with an individual radio receiver involves considerable expense. Moreover, where ordinary loudspeakers are used, one listener cannot entirely exclude the program from another instrument that is different; such arrangements in consequence have heretofore been deemed impractical.

In the practice of the present invention, the sound is reproduced by a translating device arranged to confine the sound to a finite region of space. To this end a confined transmitting medium is employed in association with the device reproducing the sound from electric impulses. By such means, each listener in a group in a room may listen to the program of his or her selection while employing a common radio energy collecting means. A sound reproducing or speaking device coupled to propagate sound in a confined transmitting medium for this purpose may be described as a "quiet speaker" to distinguish it from ordinary loudspeakers, and a radio set when equipped with one or more such arrangements, a "quiet radio". The listener, of course, places his or her head or ear against the medium and the sound is perceived without setting the air outside of the space occupied by the medium into acoustic vibration, except to a negligible extent.

To achieve the desired effects upon the ear of a listener the coupling between the speaking device and the medium is made to be relatively efficient, hence a relatively extended vibrating surface or diaphragm in the sound reproducing device is employed. Also it is advantageous to drive the diaphragm reactively. For this purpose a speaking device of the bone conduction type, that is employed as a hearing aid for the hard of hearing and which is reactively driven, may be employed. Such devices are relatively small and durable and are readily adapted for the driving of an extended surface in association with a con-

fined transmitting medium. Also to avoid undue fatigue of the listener it is desirable to have the sound transmitted by the medium reproduced at the ear of the listener with a substantially normal quality, i. e., with a so-called "flat" volume-frequency characteristic.

It has been ascertained that, when a confined transmitting medium is associated with a speaking device of the character indicated, there is produced attenuation and absorption of certain frequencies in the sound transmitted due to the damping effect of the material constituting the medium. Where the confined medium is a pillow filled with feathers, air is in fact the transmitting medium but the feathers operate to load the medium with damping agents. The medium in such case is a composite medium with a non-uniform attenuation and selective frequency absorption characteristic. The sound therefore transmitted to a person whose head is on the pillow from a speaking device reproducing sound with a normal flat characteristic will be lacking those frequencies or bands which have been absorbed and will not be perceived as sound with the normal quality desired.

To achieve the desired effect upon listeners, in accordance with the present invention, means are associated with the speaking device that is coupled to the transmitting medium which accentuate those frequencies selectively absorbed in the medium whereby the absorption is compensated for, and the sound perceived by the person listening has normal qualities.

Referring now to the drawings, and particularly to Fig. 1, 10 denotes a means, for example, an antenna, for collecting primary electric energy corresponding to the sound to be reproduced. This source of energy is shown as provided with two coupled coils 10₁ and 10₂ so that two separate sets of impulses may be selected by tuning and, when suitably amplified, reproduced by means of quiet speakers in the one room. (It is obvious that the invention is not limited to the use of two coils, any number that can be conveniently coupled electrically being employable.) The coils 10₁ and 10₂ are here shown with coupled amplifiers 11₁ and 11₂. Output coils 12₁ and 12₂ are connected to these amplifiers and preferably have inductively coupled coils 13₁ and 13₂ for supplying a common loudspeaker 14. This latter is connected to coils 13₁ and 13₂ selectively by two-throw switches 15₁ and 15₂. Each of switches 15₁ and 15₂ has its other pole respectively connected through conductors leading to plug-in devices 16₁ and 16₂, from which lead conductors 17₁ and 17₂ to quiet speaking devices R₁ and R₂ respectively. For certain uses, for example, in hospitals where the use of a loudspeaker is undesirable, it is preferable to arrange the changeover switches 15₁ and 15₂ to have the form of a hold-down or momentary contact variety so that the loudspeaker is in circuit only while the user is tuning the set. Then upon completion of the tuning, the switch will immediately return to quiet position shown in the drawings. The loudspeaker may even be dispensed with, tuning being done with the quiet speaker. Each of these devices has acoustic coupling with a confined transmitting medium; the media being shown respectively at T₁ and T₂. Such media may have the same or individually different sound attenuating and frequency absorption characteristics.

Details of one form of a suitable speaking device, such as shown at R₁ and R₂ in Fig. 1 and adapted for cooperative coupling with a confined

transmitting medium, are shown in Fig. 2. The arrangement illustrated is such that the device may readily be used in place of an ordinary loudspeaker with a radio receiver. Here conductors 17 supply the amplified electric impulses that represent sound and lead to a winding 18 which comprises the electromagnetic actuating means of the sound reproducing device. The winding 18 is disposed in a housing H which has an extended closure or diaphragm S which is adapted to be vibrated by reactive forces produced by the driving mechanism associated with winding 18 within the housing H. This mechanism is shown as a mechanical system composed of articulated members 19, 20, and 21, which comprise a tuning fork, between the prong members 19 and 21 of which is disposed the winding 18. To drive the diaphragm S, the prong member 21 is fixed to the diaphragm in any convenient manner. To support the winding 18 in driving position, it is preferably mounted on a core portion depending from the free prong member 19, there being an air gap 22 of suitable width between this portion and the prong member 21. The transmitting medium which is interposed between the diaphragm S and the ear of the person using the device is here shown at T. The sound attenuating and frequency absorption characteristics of this medium are shown in Fig. 3.

In Fig. 3, the volume of sound reproduced is denoted by ordinates, while frequency is denoted by abscissae; the values of the frequency increasing from left to right. The curve u shows the normal volume-frequency characteristic of the sound produced by any vibrating surface, when actuated to produce sound adapted to be perceived through normal air conduction by a person of normal hearing. This would also be the characteristic of the sound reaching the brain of a person hard of hearing when using a bone conduction device suited to his particular type of deafness. When an absorptive transmitting medium, such as indicated at T, intervenes, the selective absorption takes place in the higher frequencies. The propagation characteristic of the medium is indicated by the curve v, which is shown as starting at a point close to the curve u in the low frequency region, i. e. in the region of 100 cycles per second; the curve v thereafter dropping away from the curve u as the values of the frequency increase, the departure being relatively great in the high frequency region, i. e. above 1,000 cycles per second. This is due to the fact that for the medium comprising air loaded with feathers, taken by way of example, the absorption of sound increases as the frequency increases. In Fig. 3 the frequencies are shown on a logarithmic scale.

To compensate for the absorption characteristic indicated by curve v, the quiet speaker of the present invention is made to reproduce sound with an accentuated or augmented volume for those frequencies which are selectively absorbed, i. e., the speaker is made to reproduce sound with a response characteristic which is here depicted as curve w. Here, it is seen that the volume of sound reproduced by the surface S is increased for frequencies between 2,000 and 6,000 cycles per second and is above normal so that the absorption introduced by transmission through the medium T brings the volume perceived by the person, hearing through medium T, down to the level depicted in the perception characteristic curve u.

Thus, the distortion produced by the attenuat-

ing effect of a loading agent, such as feathers, and the increased output in the higher frequencies of the quiet speaker, produce the sensation at the ear of a listener of a flat response curve, such as shown at u_1 which is similar and generally parallel to the curve u . This same characteristic of reproduction by a bone conduction device produces at the brain an agreeably perfect quality for those of defective hearing who comprise the group who have appreciable nerve deafness combined with middle ear or conduction deafness. The desired compensating effects to be introduced into the sound reproduced by the speaking device of the present invention are accomplished either mechanically or electrically.

To introduce compensating effects mechanically into a quiet speaking device, the factors which control the vibration and resonance characteristics thereof are altered; for example, the stiffness of the yoke or reed member 20 may be altered and given desired values. The ratio of high frequency to low frequency may be increased by increasing the stiffness in any suitable manner, for example, by altering the cross-section of the reed or yoke member 20 to increase its thickness. Also it will be understood that the character and area of the sound radiating surface of diaphragm S may be altered in order to achieve a desired modification in the response characteristic, for example, the area of diaphragm S may be increased to increase the ratio of low frequency to high frequency energy in the sound reproduced.

To provide the desired compensating effects electrically instead of mechanically, a speaking device of the type shown at R_1 and R_2 but having substantially no resonance (i. e., none with appreciable effect), is employed and arranged to be actuated by a modified electric circuit, such as shown in Fig. 4. Here, a common antenna 18 supplies two sets of amplifying stages 11_1 and 11_2 , as in Fig. 1. Each of these stages has an output circuit and a two-throw switch, as shown at 15_1 and 15_2 in series therewith. One pole of each of these switches is connected to a common output coil 12 that is the primary of a transformer which has a secondary 13 for supplying a common loudspeaker at 14. The other poles of each of switches 15_1 and 15_2 have connections leading respectively to primaries of transformers 26₁ and 26₂ that supply coils 28₁ and 28₂ through conducting circuits 27₁ and 27₂; the coils 28₁ and 28₂ being the actuating electromagnetic means for the speaking devices that have substantially no resonance, provided in accordance with this form of the invention. The modification of circuits 27₁ and 27₂, which may be regarded as having matched impedances, is accomplished by introducing suitable elements of impedance to achieve a response characteristic in accordance with the curve w . This modification may be accomplished in any one of several ways. For example, elements of inductance as shown at L_1 and L_2 may be disposed in shunt with the coils 28₁ and 28₂ and elements of capacitance K_1 and K_2 inserted in series therewith, the values of which are chosen so that sound is reproduced by the diaphragm of the coupled speaking device with a characteristic shown by the curve u_1 in Fig. 3.

The mode of operation of the speaking devices shown in Figs. 1 and 4 is believed to be readily understood from the above description because they reproduce sound not with the normal sound characteristic depicted by the curve u but modified by accentuating predetermined frequencies so as to compensate for the distortion

unavoidably introduced by a coupled confined transmitting medium.

The response characteristic curve w which depicts that desired for a speaking device cooperatively associated with a confined transmitting medium when loaded with damping agents, such as feathers, resembles the response characteristic that it is desired to impart to a speaking device with an extended diaphragm for the propagation of sound in ordinary air, disclosed in my copending application, Serial No. 114,621, filed December 7, 1936. The device disclosed in my said copending application is of the general type here employed and is adapted for use by a person of normal hearing listening in a room and perceives sound with a normal flat characteristic. Also, a person hard of hearing and who belongs to the class whose perception of high frequencies is subnormal may use the device and perceive the sound at close range as though propagated with a normal characteristic. It will be understood, however, that this similarity is quite accidental, the shape desired for the practice of the present invention being dependent on the nature of the transmitting medium employed, the curve w , here illustrated by way of example, being that which gives the compensating response for the characteristic curve v , which depicts the propagation characteristic for a pillow filled with feathers. In the event that a different transmitting medium were used the attenuation and absorption characteristic would in general give a curve other than that depicted at v . To produce the desired effect at the ear of the listener, the distortion, whatever its nature and character, is corrected by the speaking device having a compensating response characteristic, employed in accordance with the invention.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent, is:

1. In a sound reproducing system, the combination with a transmitting medium through which a person desiring to listen may receive sound and which is of a character that attenuates sound and absorbs frequencies throughout the normal hearing range in a non-uniform manner, of a primary source of electric impulses representing sounds to be reproduced, means in association with said source for amplifying said impulses to values representing sounds of a quality and amplitude adapted for normal reproduction, an extended surface adapted to be placed in sound propagating contact with said medium, a mechanical system for vibrating said surface reactively, means for driving said system actuated electrically by said amplified impulses, and means associated with said driving means for modifying the resonance characteristic thereof and accentuating the vibrating frequencies corresponding to the frequencies absorbed by said medium.

2. In a sound reproducing system, the combination with a transmitting medium through which a person desiring to listen may receive sound and which is of a character that attenuates sound and absorbs frequencies throughout the normal hearing range in a non-uniform manner, of a primary source of electric impulses rep-

resenting sounds to be reproduced, means in association with said source for amplifying said impulses to values representing sounds of a quality and amplitude for normal reproduction, 5 an extended surface adapted to be placed in sound propagating contact with said medium, a mechanical system of members connected for vibrating said surface reactively, means for driving said system actuated electrically by said amplified impulses, the moving members of said system having a predetermined mass and stiffness so as to alter their response characteristic from that intended for normal sound reproduction to one in which selected frequencies are accentuated 10 to a degree which compensates for the frequencies absorbed by said medium.

3. In a sound reproducing system, the combination with a transmitting medium through which a person desiring to listen may receive 20 sound and which is of a character that attenuates sound and absorbs frequencies throughout the normal hearing range in a non-uniform manner, of a primary source of electric impulses representing sounds to be reproduced, means in association 25 with said source for amplifying said impulses to values representing sounds of a quality and amplitude adapted for normal reproduction, an extended surface adapted to be placed in sound propagating contact with said medium, a mechanical system of articulated members connected for vibrating said surface reactively, means for driving said system actuated electrically by

said amplified impulses including an electric circuit with balanced impedances, and means comprising elements of impedance inserted in said circuit for modifying the resonance characteristic thereof electrically and accomplishing the accentuation of vibrating frequencies corresponding to the frequencies absorbed by said medium. 5

4. In a sound reproducing system, the combination with a damping transmitting medium in a confined space and adapted for conveying sound 10 to an individual listener, of a translating device having an extended diaphragm in sound propagating contact with said medium, a vibrating mechanism floatingly coupled to said diaphragm for actuating it reactively, and means for supplying electric energy for driving said mechanism in accordance with sound to be reproduced. 15

5. In a sound reproducing system, the combination with a damping transmitting medium in a confined space and adapted for conveying sound 20 to an individual listener, of a translating device having an extended diaphragm in sound propagating contact with said medium, a vibrating mechanism comprising articulated members disposed to form a tuning fork and coupled floatingly 25 to actuate said diaphragm reactively, certain of said members being stiffened, a mass-member of appreciable weight attached to a floating member of said mechanism, and means for supplying electric energy for driving said mechanism in 30 accordance with sound to be reproduced.

STERLING G. SEARS.
